UNITED STATES PATENT OFFICE.

FRED GEITZ, JR., OF ELLINGTON, MISSOURI.

MEANS EMPLOYED IN ACCOUNTING SYSTEMS.

1,392,930.

Specification of Letters Patent. Patented Oct. 11, 1921.

Application filed October 11, 1920. Serial No. 416,072.

To all whom it may concern:

Be it known that I, FRED GEITZ, Jr., a citizen of the United States, residing at Ellington, in the county of Reynolds and 5 State of Missouri, have invented certain new and useful Improvements in Means Employed in Accounting Systems, of which the following is a specification.

This invention relates to accounting books 10 and has for its object the production of a simple book which is so arranged as to permit the user to easily and conveniently keep an accurate record of all transactions taking place from day to day, month to month, 15 and if desired from year to year.

Another object of this invention is the production of a simple and efficient accounting book whereby the various records 20 may be systematically kept and conveniently transferred from the pages containing the day record to pages containing the monthly record, and also whereby accurate record 25 may be kept of all transactions during the year for the purpose of compiling necessary data for income tax reports.

Other objects and advantages of the present invention will appear throughout the following specification and claims.

In the drawings:

30 Figure 1 is a plan view of the daily or weekly transfer sheet used in connection with the present book.

Fig. 2 is a plan view partly broken away showing one page of the book for keeping 35 a daily record of the various accounts.

Fig. 3 is a plan view of the sheet partly broken away upon which may be kept the daily records similar to Fig. 2 and constituting a continuation thereof.

40 Fig. 4 is a plan view of one of the recapitulation sheets and

Fig. 5 is a similar view to Fig. 4 showing a continuation thereof.

Fig. 6 is a plan view of the invoice sheet 45 upon which all invoices are tabulated as soon as the goods arrives and are checked up.

Fig. 7 is a plan view of the invoice sheet for keeping a monthly record thereof, and

50 Fig. 8 is a plan view of the sheet upon which may be kept the comparison statements, financial statements, and income tax report data.

It should be understood that a detached work sheet may be used in conjunction with 55 this book and that the remaining sheet com-

prising the sheet shown in Figs. 2 and 8 inclusive may be compiled in a book and bound in any suitable or desired manner. These sheets may also be used upon a loose leaf ledger if so desired without departing from 60 the spirit of the invention. By considering particularly Fig. 1, it will be seen that the separate or loose sheet is illustrated, comprising an upper section 10 for record of purchases and a lower section 11 for record 65 of sales. Each of the upper and lower sections is divided into a plurality of vertically extending columns 12, each having a legend title and each column also being alphabetically lettered. A wide column 13 is provided in both the upper and lower sections 70 10 and 11 upon which may be recorded a firm name or other description to properly identify the transactions recorded. Upon the extreme right of the page, a column indicated by the numeral 14 is employed in 75 both the upper and lower sections of the sheet to record respectively the total expenses and the total sales upon the temporary sheet. Each of these sheets of 80 course, is ruled horizontally to separate the individual record recorded thereon, and each vertical column is also ruled to correctly separate the dollars and cents in the usual way.

The book is preferably arranged in progressive formation, that is to say, the daily entrance sheets are bound near the front of the book and near the rear of the book the monthly record sheets are placed and finally 90 the yearly tabulating sheets are placed in the extreme rear of the book together with the income tax data recording sheets illustrated in Fig. 8.

At the end of each day, the items entered 95 upon the sheet shown in Fig. 1, are entered according to their alphabetical designation opposite the proper date, the entrance being made both for the goods bought and also for the goods sold. Taking for example 100 should the total amount of groceries sold during one day amount to \$570.33, this amount of \$570.33 will be placed opposite the first day of the month in column A under the column entitled "Sold". The 105 amount of groceries bought would also be recorded on the same date under the column listed "Bought". Then at the end of the month, each of these transactions would be totaled. It, of course, should be understood 110

that other items might also be listed by being transferred to proper columns agreeing alphabetically with the column upon which the entrance has been made on the temporary or work sheet shown in Fig. 1. As shown in Fig. 3 the opposite page to that employed in the book shown in Fig. 2 is illustrated wherein the merchandise, miscellaneous expenses, phone, rent, light, insurance, interest, taxes, postage, freight and express, etc., may also be recorded from day to day from the work sheet. These items are also lettered alphabetically in order to correspond with certain other alphabetical lettering appearing in other tabulating sheets used in connection with the present book.

In Figs. 4 and 5 there will be found a proper illustration of the tabulating sheet for monthly record of the various items which are recorded upon the day sheet shown in Figs. 2 and 3, each of the vertical columns being alphabetically lettered to agree with the vertical columns on the day sheets. In this way record from month to month may be kept of both goods bought and sold, merchandise received and paid for and other expenses involved from month to month. From this sheet the grand total for the year may be obtained and transferred to the yearly balance sheet shown in Fig. 8.

By referring to Fig. 2 it will be seen that the sheet is provided on the left hand margin with a series of vertically arranged numbers indicating days of the month having the legends "Today" and "To date" appearing opposite each number indicating the date of the month. Under each sub-section on each sheet shown in Figs. 2 and 3, is arranged a column 16 indicating goods bought and a column 17 indicating goods sold. Two columns may be found under each class of goods and under each alphabetically lettered column. In Fig. 3 this double column idea indicated by the numerals 18 and 19 is only employed in column I under the head of Merchandise. The other columns are single columns running from J to U, the dates of the month being located at the right hand end of the sheet indicated in Fig. 3. In Figs. 4 and 5 the sheets are ruled similar to that shown in Fig. 3, with the exception of the printing appearing upon the left and right hand ends respectively of the sheets shown in Figs. 4 and 5 wherein the days of the month are supplanted by the months of the year as indicated by the numeral 19. In Fig. 6 there is shown a page employed in connection with the present book entitled "Accounts payable invoice register" upon which the invoice accounts are recorded. A column 20 is arranged to the extreme left of the sheet to contain the date of the invoice and other columns 21 are employed in which are entered the name of the party from whom the

goods are purchased, his address, the date when due, the terms, the amount, credit, discount, freight or express charges, amount paid, date when paid, check number and finally a column indicated by the numeral 70 22 upon which suitable remarks may be entered for the purpose of keeping accurate record of the transactions.

In Fig. 7 there is a record sheet illustrated upon which a record may be kept of the date upon which the invoices are due which records are to be checked when paid. It will be seen that the upper half of the sheet illustrated in Fig. 7 is divided into columns 23 running from 1 to 16 the lower half of the 80 sheet is divided into columns 24 running from 17 to 31, to allow a proper record to be kept from day to day of the invoices as they fall due. As shown in Fig. 8 a balance sheet is provided upon which all of the transactions may be recorded for the entire year from the other sheets in the book to wit the monthly sheet, whereby the total is obtained for the entire year and then recorded in the column 25 under debits or credits opposite 90 the proper alphabetical enumeration. For instance the total amount debit for groceries would be placed opposite the column indicated A and from the column A in the corresponding sheet and placed either in the 95 debit or credit column. To the right of the column 25 will be found 2 columns 26 for entering the balance for the debit and credit. The column 25 corresponds with the alphabetical arrangement appearing upon the 100 sheet in the book keeping record of the various items for both day and monthly sheets.

By referring more particularly to Fig. 8 it will be seen that a column is arranged for keeping proper record of assets and liabilities. This column of assets contains such headings as "Cash on hand in banks," "Merchandise inventory," "Amounts receivable," "Prepaid insurance," "Notes receivable," "Buildings or property," "Fixtures and 110 equipment," and "Miscellaneous" and is indicated by the numeral 28. The liability column is indicated by the numeral 29 and contains such notations as "Proprietor," "Capital account," "Accounts payable," 115 "Notes payable," "Accrued interest payable," "Accrued salaries payable," "Accrued taxes," "Miscellaneous" and "Depreciation" from which may be obtained the total liability. The total assets may also be obtained from the assets column 28. An income tax record indicated by the numeral 30 is also employed upon the sheet illustrated in Fig. 8 to the right of the financial statement. These statements are preferably 120 arranged as follows: The comparison statement is placed to the left of the sheet, the financial statement to the right of the comparison statement and intermediate the comparison statement and income tax report, 125 130

which income tax report is preferably arranged upon the extreme right of the sheet. This income tax statement indicated by the numeral 30 has suitable legends printed thereon whereby the total amounts of the present inventory may be obtained, cost of the goods sold, salaries paid, total expenses, bad accounts, and depreciations and the ultimate profit of the business obtained. A 5 space is also left for the recordation of incomes such as real estate and bonds and a place for the recordation of the salary of the owner may also be found thereon. In this way a complete and accurate account 10 may be kept whereby the income tax reports may be accurately and properly made without the necessity of reviewing the entire book and reviewing the entire business done 15 during the previous year.

20 From the foregoing description it will be seen that a very systematic and accurate method has been produced by the compilation of the book fully described and illustrated whereby the various transactions as 25 they occur may be set accurately in a record from day to day and then promoted to a record from month to month and finally from a record for the entire year for the 30 various transactions and the proper and accurate balance may be obtained without the necessity of again reviewing the entire transactions from time to time.

It, of course, should be understood that any suitable or detailed changes may be 35 made in the mechanical construction of the book without departing from the spirit of the invention so long as these changes fall within the scope of the appended claims.

Attention is called to Figs. 2 to 5 inclusive and it will be noted that in both the daily and monthly records, the sheets are arranged in columns lettered alphabetically, these sheets being grouped in pairs, each pair comprising a right and left hand sheet, 45 the right hand columns of each left hand sheet being a column for record of bank account including deposits and checks drawn in each instance and the left hand column of each right hand sheet comprising the record for merchandise received and paid for. 50 These columns in this way may be readily compared.

What is claimed is:—

1. Means for book-keeping comprising a sheet for primarily recording transactions and divided into upper and lower sections, one section being appropriately designated for purchases and the other for sales, said sections being divided into corresponding vertical columns, the columns of each section being differentially headed for separate classes of transactions and each having a key character displayed at the top thereof, corresponding columns in the two sections being correspondingly keyed, and a sheet on which to transfer the primarily recorded transactions for permanent record, said last sheet being divided into vertical columns corresponding in number to the number of columns of the first sheet and having corresponding key characters, the purchase and sale columns of the second sheet being grouped together under a single key character, said second sheet being horizontally ruled into daily divisions. 65

2. Means for book-keeping comprising a sheet for primarily recording transactions and divided into upper and lower sections, one section being appropriately designated for purchases and the other for sales, said sections being divided into corresponding vertical columns, the columns of each section being differentially headed for separate classes of transactions and each having a key character displayed at the top thereof, corresponding columns in the two sections being correspondingly keyed, a sheet on which to transfer the primarily recorded transactions for permanent record, said last sheet being divided into vertical columns 80 corresponding in number to the number of columns of the first sheet and having corresponding key characters, the purchase and sale columns of the second sheet being grouped together under a single key character, said second sheet being horizontally ruled into daily divisions, and a third sheet 85 divided into vertical columns identical with the divisions of the second sheet and identically keyed and horizontally ruled into monthly divisions. 90

In testimony whereof I affix my signature.

FRED GEITZ, JR.
